ELECTROLUMINESCENT-FERROELECTRIC-
PHOTOCONDUCTIVE DISPLAY DEVICEJuris A. Asars, Monroeville, Pa., assignor to Westinghouse
Electric Corporation, East Pittsburgh, Pa., a corpora-
tion of PennsylvaniaFiled Aug. 23, 1961, Ser. No. 133,366
5 Claims. (Cl. 315—151)

The present invention relates to electrical-to-light transducer apparatus, and more particularly to electroluminescent-ferroelectric-photoconductive display apparatus having two stable states.

In most electrical-to-light information display transducer apparatus, which are compatible with high-information-capacity solid state display devices, the screen of the display apparatus receives electrical information from a digital data processing computer. As a result, the screen must be able to accept electrical information at a rate which is compatible with the computer, and in most cases only a bistable (ON-OFF) mode of operation is required. Because the computer must perform other functions in addition to providing electrical information to the display screen, an infinite display storage time and both selective and total erasure of old information is very desirable. Also, it is desirable to have a screen display which can be used as a memory source with read-out capabilities. The electroluminescent-ferroelectric (ELF) display screen, as known in the prior art, possesses the fast writing or access speed and selective erasure, as well as read-out capabilities; however, it lacks the infinite display storage device and the whole display cannot be non-selectively erased in a short period of time. On the other hand, the electroluminescent-photoconductor display screen, known in the prior art, has infinite display storage time and can be erased on a total display basis; however, it is not compatible with computer writing speeds and selective erasure of old information is not readily obtainable. By combining the two display methods, apparatus, as disclosed herein, may be provided with fast writing speed and infinite storage time.

It is, therefore, an object of the present invention to provide a new and improved electroluminescent-ferroelectric-photoconductor display apparatus having fast writing speed and infinite storage time.

Broadly, the present invention provides bistable electroluminescent-ferroelectric-photoconductor display apparatus in which a light output is supplied from an electroluminescent cell in response to electrical information applied as a control potential to an electroluminescent-ferroelectric circuit. A photo-conductive element is provided to be responsive to the light output as a feedback control to maintain the light output at the then present stable state.

These and other objects will become more apparent when considered in view of the following specification and drawings, in which:

FIGURE 1 is a schematic diagram of the circuitry embodied in the present invention; and

FIG. 2 is a waveform diagram used to aid in the explanation of the operation of the present invention.

Referring to FIG. 1, an electroluminescent-ferroelectric bridge circuit and excitation sources are shown including the nonlinear ferroelectric capacitors F_1 and F_2 , the electroluminescent cell EL , the alternating excitation sources e_1 and e_2 and the D.C. bias source E_1 . The waveforms for the excitation sources are also shown in FIG. 1. Letting v_L be the instantaneous voltage across the electroluminescent capacitor EL , the A.C. component of this voltage V_L is the light-producing excitation. The average or D.C. component of v_L is V_C , the control potential. Due to the nonlinearity of the ferroelectric ca-

2

pacitors and the dissymmetry of the excitation and bias sources, V_L is a function of V_C . Therefore, the amount of light emitted by the electroluminescent cell EL is dependent upon the control potential V_C .

Referring also to the waveform diagram shown in FIG. 2, for bistable (ON-OFF) operation direct control potentials must be supplied to the point f in FIG. 1 in order to establish the ON-OFF conditions. The potential e_{CON} is defined as the ON control potential, and the potential e_{COFF} is defined as the OFF control potential, as shown in FIG. 2. The potentials e_{CON} and e_{COFF} are established at the point c shown in FIG. 1. These potentials are stored on the storage capacitor C_s , and transferred through the isolation resistor R_s to the junction point f between the ferroelectric capacitors F_1 and F_2 . It is assumed in the present example that the ON potential e_{CON} is greater than the OFF potential e_{COFF} . Point g is supplied with a D.C. potential which is equal to or greater than the ON control potential e_{CON} , and point h is supplied with a D.C. potential which is less than or equal to the OFF potential e_{COFF} . A photoconductive resistor R_{pc} is connected to the resistor R_s and the resistor R_d at the common point c . The other end of the resistor R_d is connected to the point h . While the electroluminescent cell EL is in the OFF state, the resistance of the photoconductive resistor R_{pc} is greater (several times) than the resistance of the resistor R_d , and so the D.C. level at points c and f drifts in the direction of the OFF state to maintain stability in that state. However, when the electroluminescent cell EL is in the ON state, the light feedback from the electroluminescent cell EL acting upon the photoconductive resistor R_{pc} reduces the resistance of R_{pc} below that of the resistor R_d and the D.C. level at points c and f then drifts in the direction of the ON level.

In order to provide bistable operation incoming information is applied at points a and b . As shown in FIG. 2, potentials e_{aON} and e_{bON} are supplied at the points a and b , respectively, to provide the ON state, while the potentials e_{aOFF} and e_{bOFF} are supplied in order to provide the OFF state. The diodes D_a and D_b are nonconducting to maintain the stored charge on the capacitor C_s within the potential limits of e_{aON} to e_{aOFF} for point a , e_{bON} to e_{bOFF} for point b , and e_{CON} to e_{COFF} for point c .

Assuming that the electroluminescent cell is in its ON state, the control potential e_{CON} is established through the potentials e_{aON} and e_{bON} . When new information is received for the particular element, it is stored on the indirect storage capacitor C_s by applying a switching burst e_{d1} , see FIG. 2, to the point d common to the capacitor C_s in coincidence with the proper potentials e_{aOFF} and e_{bOFF} at the points a and b , respectively. The clamping action of the diodes D_a and D_b then may readjust the potential on the storage capacitor C_s to the new control potential e_{COFF} , and thus turning the electroluminescent cell EL to its OFF position. With the cell EL in its OFF position, no light feedback is provided to the photoconductive resistor R_{pc} so the resistor R_{pc} goes to its high impedance state being several times larger than the resistor R_d . The effect then is to maintain the control points c and f at the OFF condition by having the control potential drift in the direction of the potential e_{COFF} , or that at point h . Now with the electroluminescent cell EL in its OFF state and new information e_{aON} and e_{bON} being applied to the points a and b , respectively, the switching burst e_{d2} causes the storage capacitor C_s to be charged to the ON potential e_{CON} as the diodes D_a and D_b allow the capacitor to so readjust in the presence of the switching burst e_{d2} . With the cell EL in the ON condition, light feedback is then supplied, as shown in the feedback path F in FIG. 1,

thus effecting the low impedance state of the photoconductive resistor R_{pc} . In its low impedance state, the photoconductive resistor R_{pc} is lower than the resistance of the resistor R_d . The control potential at points c and f thus tends to drift in the direction of the ON potential or that at point g , thus maintaining stable operation in the ON state with the feedback path being provided to activate the photoconductive resistor R_{pc} .

While in the embodiment shown in FIG. 1 the photoconductive resistor R_{pc} and the resistor R_d are shown as separate circuit components with special input terminals, in practical circuits they may be combined with the other circuit elements. Because semiconductor diodes and electroluminescent cells are photoconductors, the photoconductor resistor R_{pc} in this circuit can be combined with either of the diode D_a or the electroluminescent capacitor EL . Similarly, the resistor R_d may be combined with the diode D_b , the storage capacitor C_s or the ferroelectric capacitor F_2 .

FIG. 1 is only illustrative of one of the many possible circuit configurations that could be utilized with the same basic concepts. Direct storage without the need for the storage capacitor C_s , could also be used. See Patent No. 3,018,412 issued January 23, 1962 to J. A. Asars and assigned to the same assignee as the instant application.

Only one element of a display screen has been specifically described herein. In order to provide a display screen a plurality of elements may be arranged in a suitable matrix to visually display incoming electrical information.

Although the present invention has been described with a certain degree of particularity, it should be understood that the present disclosure has been made only by way of example and that numerous changes in the details of construction and the combination and arrangement of parts may be resorted to without departing from the scope and the spirit of the present invention.

I claim as my invention:

1. In image display apparatus operative with information signals having two levels the combination of, storage means operative to store said information signals at either of said levels, electroluminescent-ferroelectric circuit means operative to provide a light output having either of two stable states in response to said stored information signals, storage adjust means operative with said storage means to selectively allow said storage means to adjust in response to the then present level of said information signals, and photoconductor stabilizing means responsive to said light output to maintain the then present stable state.

2. A bistable electrical-to-light transducer information signal having two levels the combination of, storage means operative to store electrical information at either of two levels, electroluminescent-ferroelectric circuit means operative to provide a light output having either of two stable states in response to said stored information level, storage adjust means operative with said storage means to selectively allow said storage means to adjust in re-

sponse to the then present level of said information, and photoconductor stabilizing means responsive to said light output to maintain the then present stable state.

3. In image display apparatus operative with information signals having two levels the combination of, storage means operative to store said information signals at either of said levels, electroluminescent-ferroelectric circuit means operative to provide a light output having either of two stable states in response to said stored information signals, storage adjust means operative with said storage means to selectively allow said storage means to adjust in response to the then present level of said information signals, stabilizing means responsive to said light output to maintain the then present stable state, said stabilizing means including a photoconductive device having an impedance proportional to the light applied thereto.

4. In image display apparatus operative with information signals having two levels the combination of, storage means operatively connected to receive said information signals and being operative to store said information signals at either of said levels, electroluminescent-ferroelectric circuit means operatively connected to said storage means and being operative to provide a light output having either of two stable states in response to said stored information signals, storage adjust means operatively connected to said storage means and being operative to selectively allow said storage means to adjust in response to the then present level of said information signals, and stabilizing means operatively connected to said circuit means and being responsive to said light output to maintain the then present stable state, said stabilizing means including a photoconductive element having an impedance proportional to the amount of light applied thereto.

5. In image display apparatus operative with information signals having two levels the combination of, storage means operatively connected to receive said information signals and being operative to store said information signals at either of said levels, electroluminescent-ferroelectric circuit means including a ferroelectric capacitor connected to an electroluminescent capacitor with a common control junction therebetween to which said stored information signals are applied, said circuit means operatively connected to said storage means and being operative to provide a light output from said electroluminescent capacitor having either of two stable states in response to said stored information signals, storage adjust means operatively connected to said storage means to selectively allow said storage means to adjust in response to the then present level of said information signals, and stabilizing means responsive to said light output, said stabilizing means including a photoconductive device having an impedance proportional to the amount of light applied thereto, with said device being connected to said control junction and being responsive to maintain the then present stable state.
